UNITED STATES PATENT OFFICE

115,486

DESIGN FOR A HAT

Nathan Du Bow, New York, N. Y.

Application April 30, 1938, Serial No. 76,903

Term of patent 3½ years

To all whom it may concern:

Be it known that I, Nathan Du Bow, a citizen of the United States of America, residing at New York, county and State of New York, have invented a new, original, and ornamental Design for a Hat, of which the following is a specification, reference being made to the accompanying drawing, forming a part thereof.

Fig. 1 is a side perspective view of a hat embodying the invention, and

Fig. 2 is a rear view thereof.

I claim:

The ornamental design for a hat, substantially as shown.

NATHAN DU BOW.
